Primary Examiner — Joseph Kukella*Assistant Examiner* — Heather Wencl(74) *Attorney, Agent, or Firm* — Charles T. J. Weigell,
Esq.; Fross, Zelnick, Lehrman & Zissu, PC(57) **CLAIM**

The ornamental design for a wearable tag detacher as shown and described.

DESCRIPTION

FIG. 1 is a front perspective view of a wearable tag detacher showing our new design;

FIG. 2 is a back perspective view thereof;

FIG. 3 is a front view thereof;

FIG. 4 is a back view of the wearable tag detacher, as inverted;

FIG. 5 is a right side view thereof, with the left side being a mirror image;

FIG. 6 is a top view thereof; and,

FIG. 7 is a bottom view thereof.

The broken lines in the figures depict portions of the wearable tag detacher that form no part of the claimed design.
